(57) **CLAIM**

I claim the ornamental design for a hand held massager with rotatable head, as shown and described.

DESCRIPTION

FIG. 1 is a top plan view.

FIG. 2 is a bottom plan view.

FIGS. 3 and 4 are left and right side elevational views.

FIGS. 5 and 6 are top and bottom plan views, respectively, showing the rotatable head in a first rotational position.

FIGS. 7 and 8 are top and plan views, respectively, showing rotatable head in a second rotational position; and,

FIG. 9 is a perspective view.
